Attorney

UNITED STATES PATENT OFFICE.

JOHN RUNSBERG, OF HOPKINS, MINNESOTA.

PIPE WRENCH.

Application filed August 23, 1922. Serial No. 583,876.

To all whom it may concern:

Be it known that I, JOHN RUNSBERG, a citizen of the United States, residing at Hopkins, in the county of Hennepin and 5 State of Minnesota, have invented a new and useful Pipe Wrench, of which the following is a specification.

This invention relates to wrenches of the type adapted for use either as a nut or a 10 pipe wrench.

The object of the invention is to provide a simply constructed, cheaply manufactured, strong, powerful wrench which is easily adjusted and operated, and which grips 15 strongly and releases easily and in which the strain is equalized on the different parts of the wrench.

Another object is to provide a wrench of this type in which the acting face of the 20 movable jaw may adjust itself to various angles relative to the fixed jaw for use as a pipe wrench and in which there are no small parts such as are liable to break or get out of order.

Another object is to provide a wrench 25 having a movable jaw mounted in a bearing box which is made exceptionally strong where the strain is heaviest and so constructed that it will not spread or warp and 30 will equalize the strain on the wrench, and which eliminates the pressure of the movable jaw on the stationary jaw by allowing a straight pull on the pipe or nut and consequently a maximum power is obtained 35 with a minimum danger of breakage.

With the foregoing and other objects in view, which will appear as the description proceeds, the invention resides in the combination and arrangement of parts and in 40 the details of construction hereinafter described and claimed, it being understood that, within the scope of what is claimed, changes in the precise embodiment of the invention shown can be made without departing from the spirit of the invention.

In the accompanying drawings:

Figure 1 represents a side elevation of a wrench constructed in accordance with this invention, with the movable jaw shown in 50 full lines in gripping position and in dotted lines in the positions which it assumes while obtaining the gripping effect;

Fig. 2 is a transverse section taken on the line 2—2 of Fig. 1;

Fig. 3 is a detail longitudinal section

through the bearing box with the jaws broken off;

Fig. 4 is a detail perspective view of one of the journal members; and

Fig. 5 is a similar view of the other member of the journal.

In the embodiment illustrated the main body member 1 is of any desirable form, size and construction and is here shown provided at one end with a fixed jaw 2 having a 60 convexed toothed gripping member 3 pivotally mounted thereon. This body member 1 also has a handle 4 such as is ordinarily found in wrenches of this character.

A bearing box 5 projects laterally from 70 one edge of the body 1 near the fixed jaw 2. This box is cylindrical in form and has therein diametrically opposite openings 7 and 8 which extend parallel with the body 1 and through which the shank 36 of the 75 movable jaw 35 is designed to move longitudinally.

Mounted in the casing 6 of the box 5 is a journal member composed of two separably connected members 10 and 20 which when 80 assembled form a unitary structure and operate as a journal in the box 5 for the movable jaw 35 and which is connected therewith in a manner presently to be described.

The journal member 10 is cylindrical in 85 form, the body 11 of which fits in the casing 6 at one end thereof and is equipped with a radially extending flange 12 which when the parts are assembled overlies one end of the casing. A lug 13 extends radially from 90 the flange 12 and is designed to cooperate with a boss or lug 9 on one face of the body member 1 to operate as a lock for the movable jaw and to limit the turning of the journal in the bearing box. This member 10 95 has a rectangular opening 14 therein which registers with a similar opening 24 in the member 20 and in which is housed the adjusting nut 30 which operates on the shank 36 of the movable jaw 35.

The member 10 has diametrically opposite recesses 15 and 16 formed on its inner face at opposite sides of the opening 14 to provide in connection with similar recesses 25 and 26 in the member 20 a seat for the shank 36 of the movable jaw to permit said shank to reciprocate longitudinally therein and hold it against lateral movement. The inner face of the member 10 is also provided with bosses 17 and 18 arranged at the ends 110

of the slot-like opening 14 being diametrically opposite each other and which have threaded apertures 19 extending therethrough and through the outer face of the member to receive fastening screws 31 which connect the members 10 and 20 and hold them against accidental separation. The inner faces of the bosses 17 and 18 and the end walls of the opening 14 are inclined 10 outwardly as shown at 17^a and 18^a which in connection with similar faces 27^a and 28^a on the member 20 form a seat for the adjusting nut 30 and prevent it from dropping out of the box. 15 The member 20 which is complementary to the member 10 has the body 21 thereof of the same size and shape as the body 11 of the member 10 so that when these members are united they will form a unitary 20 structure cylindrical in shape. The member 20 has an opening 24 corresponding to the opening 14 in the member 10 to provide for the projection therethrough of the adjusting nut. On opposite sides of this opening are formed recesses 25 and 26 in the inner face of the member and at the ends of said opening recesses 27 and 28 are formed of less depth than the recesses 25 and 26 and which are designed to receive and interlockingly engage the bosses 17 and 18 of the member 10. Threaded apertures 29 extend transversely through the member 20 at the bottoms of the seats 27 and 28 and are designed to register with the apertures 35 19 in the member 10 to receive the screws 31.

The member 20 has a radially extending flange 22 flush with its outer face which overlies one face of the box 5 and which has a radially extending lug 23 designed to be positioned opposite the lug 13 of the member 10 when these members are assembled. These lugs 13 and 23 are designed to engage bosses 9 on opposite faces of the body 1 adjacent the casing 6 and the lugs and bosses 45 have their meeting faces beveled as is shown clearly in Fig. 1 to form a close joint when engaged.

The movable jaw 35 is hooked shaped or curved as shown in Fig. 11 the gripping face thereof being concaved to cooperate with the convex gripping face of the jaw 2. This concaved gripping face 39 is equipped with ratchet teeth which extend in a direction opposite to those of the gripping member 3 to insure a positive engagement of the pipe or other article to be gripped thereby.

The shank 36 of the movable jaw is provided on opposite edges with threads 37 which are designed to cooperate with the threaded interior of the nut 30 so that when the nut is rotated the shank will be moved

in or out to vary the position of the movable jaw relatively to the fixture.

It will thus be seen that when the movable jaw is mounted in the bearing box 5 and has been adjusted to accommodate the pipe or other article to be engaged, said jaw will pivot in the casing 6 being limited in its opening movement by the engagement of the shank 36 with the inner walls of the 65 openings 7 and 8 and in its closing movement by contact of the lugs 13 and 23 with the bosses 9. Obviously the outward swinging of the movable jaw will release it from its clamping engagement while its inward movement will cause it to securely grip the pipe between it and the jaw member 3.

The mounting of the movable jaw in the bearing box 5 in the manner above described 80 operates to equalize the strain on the different parts of the wrench and the peculiar construction of the journal members 10 and 20 and their engagement prevents all possibility of warping or spreading of the parts and also permits a straight pull to be exerted on the object gripped by the wrench thus eliminating the pressure of the movable jaw on the stationary jaw.

A leaf spring 32 is preferably fastened 90 with a set screw in the front part of the bearing box for the purpose of retaining the movable jaw tight against the pipe should the wrench be operated with one hand.

From the above description it will be obvious that the wrench is self-locking and 95 will not crush or damage the pipe even under the greatest pressure.

I claim:

In a wrench of the class described, a body member having a fixed jaw at one end, a 100 bearing box projecting laterally from one edge of said body and having diametrically opposite openings extending parallel with said body, a journal member mounted in said box and composed of two separably 105 connected complementary sections forming when united a unitary cylindrical structure, said sections having registering openings, an adjusting nut mounted in said openings, a movable jaw having a shank extending 110 through said box and nut whereby the turning of the nut will adjust the movable jaw toward and away from the fixed jaw and cooperating lugs carried by the box and said body to lock the jaws in gripping relation. 115

In testimony that I claim the foregoing as my own, I have hereto affixed my signature in the presence of two witnesses.

JOHN RUNSBERG.
